UNITED STATES PATENT OFFICE.

ADOLPH MOLNAR, OF NEW YORK, N. Y.

DESIGN FOR FUR-TRIMMING.

Specification forming part of Design No. **7,064**, dated December 16, 1873; application filed August 30, 1873.
[Term of Patent 3½ years.]

To all whom it may concern:

Be it known that I, ADOLPH MOLNAR, of the city, county, and State of New York, have invented a new and useful Improvement in Design for Fur-Trimming; and I do hereby declare that the following is a full, clear, and exact description of the same, reference being had to the accompanying drawing forming a part of this specification, in which—

Figure 1 represents my design for fur-trimmings for ladies' fur-jackets.

The object of my design is to embellish fur-jackets, and other articles of fur, to produce a new and striking effect, and cause the appearance of those garments to be greatly improved.

A, in the drawing, represents a loop, made of a fur-covered string, which is obtained by winding around the inner string B the strip C, of seal or other fur.

Having thus described my invention, what I claim as new, and desire to secure by Letters Patent, is—

The design for fur-trimming, above described and shown.

ADOLPH MOLNAR.
